DESIGN FOR A COMBINATION GRILL AND COOKING TOP FOR GAS STOVES

George Finn, Newark, N. J.

Application August 12, 1935, Serial No. 58,094

Term of patent 7 years

To all whom it may concern:

Be it known that I, George Finn, a citizen of the United States and a resident of Newark, in the county of Essex and State of New Jersey, have invented a new, original, and ornamental Design for a Combination Grill and Cooking Top for Gas Stoves, of which the following is a specification, reference being had to the accompanying drawing, forming part thereof.

Figure 1 is a top plan view of a combination grill and cooking top for gas stoves, showing my new design.

Figure 2 is an edge view of Figure 1 showing the openings therein, and

Figure 3 is a section on the line 3—3 of Figure 1.

I claim:

The ornamental design for a combination grill and cooking top for gas stoves as shown and described.

GEORGE FINN.
